[57] CLAIM

The ornamental design for a suspendible receptacle, as shown and described.

DESCRIPTION

FIG. 1 is a front perspective view of a suspendible receptacle showing my new design, the rear being flat and unornamental;

FIG. 2 is a side elevational view taken from the right of FIG. 1; and

FIG. 3 is a top plan view thereof.

The cross-line shading which is partially shown in FIG. 1 is understood to represent conventional fabric and repeat across the entire surface.
